FIG. 1 is a left-front perspective view of an embodiment of

the present invention;

FIG. 2 is a front elevational view of the faucet and keystone handle assembly of FIG. 1;

FIG. 3 is a rear elevational view of the faucet and keystone handle assembly of FIG. 1;

FIG. 4 is a right side elevational view of the faucet and keystone handle assembly of FIG. 1 and is a mirror image of the left side of the faucet and keystone handle assembly of FIG. 1; and,

FIG. 5 is a top plan view of the faucet and keystone handle assembly of FIG. 1.

The broken lines contained in the Figures are for illustrative purposes only and form no part of the claimed design.
